UNITED STATES PATENT OFFICE.

SPENCER C. CARY, OF BROOKLYN, NEW YORK, ASSIGNOR TO CARY MANUFACTURING CO., OF BROOKLYN, NEW YORK, A CORPORATION OF NEW YORK.

BINDER CONNECTION.

Application filed December 9, 1919. Serial No. 343,554.

To all whom it may concern:

Be it known that I, SPENCER C. CARY, a citizen of the United States, residing at the city of New York, borough of Brooklyn, 5 county of Kings, and State of New York, have invented a certain new and useful Binder Connection, of which the following is a specification.

This invention is a device for connecting 10 or joining the end portions of a binder for shipping packages.

In this art it is required that the binder be applied under tension to a package with a view to drawing the components of the 15 package into firm relation one to the other. Difficulty has been experienced in uniting the end portions of the binder while it is under tension for the major part of its length around the package, and it is the object of my invention to supply a connection 20 by which the binder ends can be locked, or locked and sealed, in a simple, efficient and expeditious manner.

To these ends, the invention consists of a 25 sleeve into which the end portions of the binder are inserted, said end portions being twisted into locking engagement with said sleeve.

Other features and advantages of the invention will appear from the annexed description taken in connection with the drawings, wherein:—

Fig. 1 is a plan view illustrating a binder with my lock, or lock and seal, applied in 35 a closed condition.

Fig. 2 is a view illustrating the method of adjusting the lock or seal prior to twisting the end portions of the binder.

Fig. 3 is a perspective view of the lock or 40 seal detached from the binder.

Fig. 4 is a cross section through the lock or seal.

A designates a binder and B is a lock or seal for the end portions of said binder. As 45 herein shown, the binder is a wire, usually of circular cross section and of relatively small diameter. Said binder is applied under tension to the shipping package, for which purpose I have designed and used a 50 stretcher of one form or another as disclosed in prior applications for patents. By the operation of an appropriate implement, the binder is stretched for the major part of its length around a shipping package, the end 55 portions of said binder being free or un-

confined. As a matter of practical operation, the binder is of such length that when stretched the end portions will overlap to an appreciable extent, and as said lapping end portions are free from the tension exerted by the stretching implement, the operator is enabled to apply the lock and seal easily to said end portions either before or after the stretching operation, and, moreover, said end portions are readily and 60 quickly bent into the required locking contact with the seal.

As shown, the lock and seal is a sleeve, and in a preferred form, it is a double sleeve. The seal, in one form is bent or struck up 70 from a single piece of flat sheet metal, the same being folded or creased along the median line of the sleeve so as to produce a channel or groove b, and the metal on the respective sides of the groove is then doubled 75 or folded to produce the parallel tubular members c d, the edges of the metal meeting along the line e, and producing a double sleeve as a single unitary article. Said sleeve, or double sleeve, is provided at one 80 end with a notch f in the metal of the tubular member c, whereas the sleeve is provided at the other end with a notch g in the metal of the other tubular member d. The function of said notches is to receive the bent or 85 twisted end portions of the binder, and to retain the same in the required relation to the sleeve, i. e. to preclude the binder ends from becoming bent or deflected outwardly 90 relatively to the shipping packages and to keep said end portions into close and substantially parallel relation to the seal.

The binder is positioned around the package in any desired manner or by any preferred means, and before or after placing 95 said binder under tension, the double sleeve is slipped over and upon the adjacent end portions of the binder. In the practical operation of applying the binder, it is placed around the package, and certain grippers of a stretching tool are engaged with the end portions of said binder. Prior to operating the stretching tool, the double sleeve is adjusted by inserting one end of the binder into the tubular member c whereas the other 100 end portion of the binder is inserted into the other tubular member d, said two end portions passing in opposite directions through the respective members of the double sleeve. The stretching tool is now operated for plac- 105 110

ing the required tension upon the binder, drawing it into contact tightly with the shipping package, in fact, the binder is drawn so tightly as to embed it into the material of said package, particularly at the corners thereof. The effect of stretching the binder is to compress the shipping package and to draw upon the binder near the ends so as to cause said end portions to project beyond the opposite end portions of the sleeve, see Fig. 2. The protruding end portions of the binder are free from the strain of the stretching tool, and said protruding ends are bent or twisted backwardly into locking engagement with the end portions of the sleeve. For this purpose it is preferred to use a tool of a character disclosed in a copending application, filed even date herewith, by the operation of which tool the two end portions of the wire are bent in opposite directions and simultaneously, one end portion of said binder being turned in one direction, as at *h*, alongside the tubular member *c*, whereas the other end portion of the binder is turned in an opposite direction as at *i* alongside the other tubular member *d*, see Fig. 1. In the operation of twisting the end portions *h i* of the binder, the loops in the binder are forced into the notches *f g*, and said ends *h i* are bent into parallel relation to the sleeve so as to lie in the plane thereof and to occupy positions close to the surfaces of the sleeve. The ends *h i* of the binder are thus locked with the notched end portions of the double sleeve, in a manner to minimize any displacement of the bent end portions during the operations of handling and shipping the package; in fact, the twisted ends of said binder are out of the way and locked in place securely so that they cannot be pulled apart, nor is it possible to break the seal without affording evidence of the attempt to tamper with it.

From one standpoint, it is possible to use a single sleeve of the required length and possessing such diameter as to receive the two ends of the binder; but the double sleeve is considered desirable for the reason that each end of the binder can be threaded or passed through said sleeve without interference with by the other end portion of said binder, the wall of the sleeve which intervenes the two tubular members acting as a separator to preclude contact and interference when applying the sleeve to the binder, or vice versa.

It is desired to call attention to the fact that in my binder connection there is no deformation of the sleeve or tubular element in order to lock and seal the respective end portions of the binder. On the contrary, the sleeve remains in its original form after sealing the binder, but the end portions of said binder are, by a simple and easily per-

formed operation, locked to the sleeve so as to securely seal and lock the binder in order to keep the ends from pulling out of the sleeve under the tension of the binder and the strain to which said binder is subjected when the package is handled, shipped or stored.

Having thus fully described the invention, what I claim as new and desire to secure by Letters Patent is:

1. A binder seal embodying a body portion composed of a single piece of metal folded upon itself and producing a plurality of non-compressible tubular members positioned side by side and spaced in permanent relation one to the other by an intervening wall.

2. A binder seal embodying a portion composed of a single piece of metal folded upon itself and producing a plurality of non-compressible tubular members and a wall intervening said tubular members and separating the passages therein, each tubular member being provided with a binder-receiving notch in the wall at one end portion thereof.

3. A binder seal embodying a one-piece construction comprising a plurality of non-compressible tubular members and a wall intervening said tubular members, said wall separating the passage of one member from the passage of the other member, one tubular member being provided with a notch in one end thereof and the other tubular member being provided with a notch in that end thereof opposite to the notch in the first named member.

4. A binder seal embodying a one piece construction comprising a plurality of non-compressible tubular members and a wall unitary with said tubular members and separating the passages therein, said seal being provided on the outer faces of said tubular members with notches, one of which is at one end of one tubular member and the other of said notches being at the opposite end of the other tubular member.

5. In a binder seal, a sleeve comprising a plurality of tubular members lying in the same transverse plane, each tubular member having a notch in one end portion thereof, and a binder the respective end portions of which are thrust through the tubular members and are doubled backwardly for said doubled portions to be received within the notches whereby the binder ends are interlocked separately against rotative movement with respect to the sleeve.

6. As a new article, a non-compressible binder seal composed of a single piece of metal bent to form a flat web and doubled to produce a plurality of tubular members the openings in which are separated by an intervening metal wall, said tubular members lying in the same transverse plane and

each tubular member being provided in one end portion thereof with a binder-receiving notch.

7. As a new article, a non-compressible binder seal composed of a single piece of metal bent to form a flat web and doubled to produce a plurality of tubular members the openings in which are separated by an intervening metal wall, said tubular members being parallel to each other and said members being in a plane substantially parallel to the flat web.

8. As a new article, a non-compressible binder seal comprising a flat web and a plurality of tubular members the openings in which are separated by an intervening wall which is independent of the flat web, the latter constituting in part the boundary of the openings in the respective tubular members.

9. In a binder seal, a non-compressible sleeve comprising a flat web and a plurality of tubular members unitary with the flat web, said tubular members being each provided with a notch, the notch of one tubular member being in the end portion thereof opposite to the notch in the end portion of the other tubular member, and a binder the end portions of which are doubled into locking engagement with the notches in the tubular members of the seal, said locking engagement of the doubled binder with the tubular members operating to retain said binder against rotative movement with respect to the sleeve. 25 30 35

In testimony whereof I have hereunto signed my name this 3rd day of December, 1919.

SPENCER C. CARY.
